US00D581255S

(12) **United States Design Patent**
Calvin

(10) **Patent No.:** **US D581,255 S**
(b5) **Date of Patent:** **** Nov. 25, 2008**

(54) **CORD RETAINER**

(76) Inventor: **Edmund Calvin**, 37 Hoinski Way,
Ansonia, CT (US) 06401

(**) Term: **14 Years**

(21) Appl. No.: **29/304,385**

(22) Filed: **Feb. 29, 2008**

(51) **LOC (8) Cl.** **08-08**

(52) **U.S. Cl.** **D8/356**

(58) **Field of Classification Search** **D8/105, D8/107, 333, 349, 354, 356, 358, 360, 360.1, D8/367, 373, 382, 383, 394–396, 400; D23/261; D26/38; 24/18, 197, 561; 174/153 G, 650, 174/656, 135; 242/400.1, 405.1, 405.2, 600, 242/603, 604, 604.1, 607, 608, 608.6, 608.7, 242/609, 916; 248/65, 74.1–74.4, 201, 214, 248/215, 229.26, 302, 304, 316.7, 316.8; 439/367, 369, 371, 472; 211/119; D13/153; 224/268, 269, 666**
